UNITED STATES PATENT OFFICE.

WILLIAM F. WENT, OF COLORADO SPRINGS, COLORADO.

TIME FEEDER FOR DOMESTIC ANIMALS.

Application filed August 1, 1924. Serial No. 729,563.

This invention relates to improvements in means for automatically feeding poultry, stock, or the like at predetermined intervals without the intervention of human aid.

- 5 A further and important object of this invention is the provision of a novel type of feeder embodying gravity operated closure means and a timing mechanism for tripping the same at predetermined intervals.
- 10 A further and important object of this invention is the provision of an improved feeder construction including closure means for operation by a novel type of trip mechanism which may be set to operate at any 15 predetermined time.

Other objects and advantages of this invention will be apparent during the course of the following detailed description.

- In the accompanying drawing, forming a 20 part of this specification, and wherein similar reference characters designate corresponding parts throughout the several views, Figure 1 is a cross sectional view taken through the improved feeder, showing the 25 relation of details thereof.

Figure 2 is a rear elevation of the improved stock feeder, showing the regulating closure means thereof in shut position.

- Figure 3 is a similar elevation of the 30 improved feeder details with the closure regulating means tripped and open.

Figures 4 and 5 are respectively cross sectional views taken on their respective lines in Figures 2 and 3 of the drawing.

- 35 In the drawing, wherein for the purpose of illustration is shown only a preferred embodiment of this invention the letter A may generally designate the improved feeder which may include a housing B; gravity 40 operated closure means C; and means D for tripping the gravity operated closure means C to release a quantity of feed from the housing B at a predetermined time.

The housing B is preferably constructed 45 of any approved material such as sheet metal, wood, or the like, and may include a bottom 10 supported in a horizontal plane by legs 11. Front and rear walls 12 and 13 are respectively provided in attachment with 50 the bottom 10, and opposite side walls 15 and 16 are also provided, the lower edges of which terminate just upwardly of the plane of the bottom wall 10. Control doors or closure members 18 and 19 are respectively 55 pivoted, as at 20, to the opposite side edges of the bottom 10, which are adapted to regu-

late the lower corner openings 21 and 22 respectively provided at the right and left lower corners of the housing B, and which when in set position are upwardly inclined 60 from their hinged connection 20, and at their forward ends extend outwardly from the planes of the side walls 15 and 16, substantially as is illustrated in the drawing. They are of course so positioned that incident to their own weight they will drop to an open position.

Within the compartment 25, of the housing B, inclined walls 28 and 29 are provided in V-shaped relation, diverging from their upper apex end edges 30 toward the lower edges thereof and the openings 21 and 22 respectively, so that they may act in hopper manner to convey the feed from the storage compartment 25 towards the openings 21 75 and 22. It is apparent that the feed in the compartment 25 will rest against the closure members 18 and 19, and the weight of the food will also assist in opening said doors when they are released by the means C to be 80 subsequently described.

Referring to the novel gravity closure operating means C, the trap doors or closure members 18 and 19 are of course a part thereof, and the same furthermore consist of a substantially cross-shaped member including the horizontally disposed cross arm 35, having an upwardly extending vertically disposed guide arm 36 provided with a slot 38 longitudinally therein which receives a headed guide pin 39 therethrough; the pin 39 being supported by and outwardly extending from the back or rear wall 13 of the feeder housing B. A depending vertical guide arm 40 is also provided below 95 the cross arm 35, having the slot 41 extending therealong and open at the free end of the arm 40, which slidably receives the rotatable shafts 42 and 70 of the means D therethrough; the shafts 42 and 70 and 100 the pin 39 being in vertical alignment, and extending through the slots 38 and 41 to guide the movement of the cross-shaped member in its movement at the exterior side of the rear wall 13. One free end of the cross arm 35 is pivotally connected with the closure lid 19 by means of a link 45, whereas the opposite end of the cross arm 35 is operably connected with the closure lid 18 by means of a cross link 46. The 110 weight of the cross-shaped member is of course such that it will operate on the lids

18 and 19 through the medium of the connecting links 45 and 46 in order to maintain said lids open.

A detent member 50 is pivotally connected on a stub shaft 51 intermediate its ends, at the outer side of the rear wall 13 of the feeder housing B, which at one end portion thereof is adapted to cooperate against the lower edge 53 of the guide arm 40, to hold the cross-shaped member in an elevated relation with the closure members 18 and 19 closed over the openings 21 and 22; the detent member 50 being regulated by a clock controlled trip mechanism to 15 be subsequently described.

Referring to the means D, the same includes a clock mechanism 60, which is supported within the compartment 61 between the sloping hopper walls 28 and 29, upon standards 62 carried by the bottom wall 10. This clock mechanism 60 includes the casing 63 within which the ordinary spring or other operating mechanism is received, and which includes a central shaft arrangement 65 upon which the minute and hour hands 66 and 67 are mounted for cooperation over the main face portion of a dial 68. The clock mechanism furthermore includes a shaft 70 rotatably supported by 30 the stationary frame portion 71 of the clock mechanism, and at the forward end the shaft 70 supports an indicator arm 72 which cooperates over a time setting dial 73 delineated upon the main dial 68. At its rear 35 end the shaft 70 extends through the rear wall 13 of the housing B, and has a thumb nut 75 supported thereon. This shaft 70 as above mentioned extends through the slot 41 of the depending arm 40.

40 The clock operated mechanism includes a driven gear 80, rotatably supported on a stationary portion 81 of the frame 71, including a series of gear bars 82 adapted to mesh with a gear 85 which has a frictional driving fit on the shaft 70, although this gear 85 may slide longitudinally on the shaft 70 for a purpose which will be subsequently described. As a part of the gear 85 a cam 86 is provided, having a 45 plane side or top surface 87 with a recess 88 inwardly thereof, one side of the recess ending in an abrupt shoulder and the other inclining on an even slope into the plane of the surface 87. A cam arm 91 is fixed on the shaft 70, in radially extending relation therefrom, adapted to cooperate over the plane surface 87, and within the recess 88 of said cam 86, as will be subsequently described.

60 A spring 100 is carried at one end 101 upon the frame 81 of the clock mechanism, and engages the gear 85 on the opposite side thereof from the cam details 86 and 91. This spring normally forces the cam body 65 86 into engagement with the cam part 91 of

the shaft 70, and the spring at its free end 104 is pivotally connected with a retainer rod 105. The retainer rod 105 extends rearwardly from its pivoted connection 104 through a suitable bushing 106 carried by 70 the rear wall 13 of the feeder B, and is adapted for cooperation with the detent 50 on the opposite side of the stub shaft 51 with respect to that part which cooperates against the lower edge 53 of the closure 75 operating construction C.

Referring to the operation of this invention, if it is desired to feed the poultry or other live stock at say twelve o'clock, the operator grasps the thumb nut 75 and rotates the shaft 70 until the indicator 72 is positioned to designate twelve on the delineated dial 73. In this position the cam arm 91 has been moved over the plane surface 87 of the cam 86. The clock mechanism of course operating through its train of gears rotates the gear 85 and the cam 86 therewith, and the cam recess 88 will move toward the cam extension 91, and when the recess 88 reaches the predetermined positioning of the cam extension 91, the spring 100 will push the gear 85 along the shaft 70 and snap the cam 86 into position with the cam extension 91 placed in the recess 88. Movement of the spring 100 operates the retainer 95 rod 105 in like manner, withdrawing the same from its retaining position against an end of the detent 50, so that the latter will release the detent retained cross-shaped member, and the latter operated by gravity, as well as assisted by the weight of the lids 18 and 19 will open the latter for releasing the quantity of feed within the compartment 25. It is of course readily understood that the operation of the clock mechanism is not interfered with by the opening of the closure members, as the cam surface 87 rides over the pin 91 to permit the clock to operate.

From the foregoing description of this invention it is apparent that a novel type of feeder has been provided, operating with a novel type of closure means time controlled by means of novel tripping and detent mechanism.

Various changes in the shape, size, and arrangement of parts may be made to the form of the invention herein shown and described, without departing from the spirit of this invention or the scope of the claims.

I claim:

1. In a feeder of the class described a housing providing a storage compartment having openings at the lower opposite corners thereof, lids pivotally connected to said housing normally operated by their own weight to assume an open relation, a cross-shaped member carried by said housing for vertical movement and including oppositely disposed side arms, links connecting the op- 125 130

posite ends of said side arms with said lids so that the weight of said cross-shaped member will act upon said lids to hold them in an open relation with respect to the openings 5 of said housing, and time controlling means for operating said cross-shaped member.

2. In a feeder of the class described a housing having oppositely disposed corner openings at the lower corners thereof, hopper means in the housing for directing feed toward said openings, lids for each of said corner openings, a substantially cross-shaped lid cooperating member including vertical arm portions and oppositely disposed horizontal side arms, means slidably

connecting the vertical arm portions on the housing for guiding the movement of the cross-shaped member in vertical direction upon said housing, links movably connected with the side arm portions and with said lids 20 whereby to open and close the lids depending upon movement of said cross-shaped member, a time controlling mechanism carried by the housing, and trip means cooperating between the time controlling mechanism and cross-shaped member to release the latter at a predetermined time for opening said lids. 25

WILLIAM F. WENT.
